UNITED STATES PATENT OFFICE.

MARTIN MILLER, OF COLUMBUS, OHIO.

KEY-ACTION.

No. 851,894.

Specification of Letters Patent.

Patented April 30, 1907.

Application filed November 28, 1905. Serial No. 289,470.

To all whom it may concern:

Be it known that I, MARTIN MILLER, a citizen of the United States, residing at Columbus, in the county of Franklin and State of Ohio, have invented a new and useful Key-
5 Action, of which the following is a specification.

The object of the invention is the provision of certain new and useful improvements in the action, whereby the hammer is permitted to rebound from the string and remain in its inactive position while the free end of the key is depressed. In this connection, it is proposed to materially simplify the action so as
10 to reduce to the minimum the liability of the same getting out of order, and at the same time to insure the prompt and effective response of the hammer to the depression of the key.

With these and other objects in view, the present invention consists in the combination and arrangement of parts as will be hereinafter more fully described, shown in the accompanying drawings and particularly pointed out in the appended claim.
25

In the drawings: Figure 1 is a vertical sectional view thereof of the key action. Fig. 2 is a view of the action with the key depressed and the hammer in engagement with the string. Fig. 3 is a similar view showing the key depressed with the hammer in its normal position.
30

Like characters of reference designate corresponding parts in all of the figures of the drawings.
35

The sounding element of the present instrument includes a hollow sounding board or box 1 having strings stretched thereon in any suitable or approved manner. It is proposed to support the sounding element in an upright position by means of a base which includes a bottom 2, a back 3, and opposite ends 4, the top and front of the base being open or closed as desired. Each of the ends 4 is provided with an upright slot 5 intersecting its top edge and constituting a seat for the reception of the bottom of the sounding element, whereby the latter is supported in an upright position and may be conveniently
40 assembled with the base and removed therefrom without disconnecting any fastening devices.
45

In connection with the sounding board and strings, it is essential, to the most effective operation of the instrument, that each string be struck by its hammer at a point
50

one-seventh of its length from the bottom thereof, wherefore I have provided a construction best shown in Fig. 5 of the drawings, wherein it will be noted that the left hand end of the bottom of the sounding board or box is horizontal, as at G from which it is inclined upwardly from left to right, as at H, and provided at its right hand end with a depending post or leg 6 to rest in the adjacent seat 5 and support the sounding element in an upright position. The strings pass around and are connected to the bottom of the sounding board in any appropriate manner, and are decreased in length from left to right and are proportioned so that the horizontal striking line of the series of hammers, designated by the dotted line A—A, in Fig. 5, is one-seventh of the length of each string from the lower end of said string.
75

The hammer 7 of the present invention is carried at the upper end of a hammer bar 8 which latter is provided at its lower end with a hammer block 9 fulcrumed upon a horizontal support 10, preferably in the nature of a rod or bar extending between and carried by the ends of the base. Normally, the head of the hammer rests against a stop rail 11 carried by the ends of the body in front of the sounding board, there being a dead cushion 12 provided upon the rear side of the rail for engagement by the hammer head to prevent rebounding of the hammer therefrom. This cushion consists of a case having a suitable filling, such for instance, as sand which is non-elastic and therefore the hammer does not tend to rebound from the rail.
85

For each hammer there is a key 13 of the usual type which is fulcrumed intermediate of its ends upon a rod or bar 14 extending between and carried by the ends of the base. The inner free end portion of the key is provided with a longitudinal upright socket or slot 15 in which is disposed an upright jack 16 which has its lower end pivoted within the socket as at 17, there being a spring 18 located in the socket and bearing against the front wall thereof and the front edge of the finger to yieldably maintain the latter in an upright position.
95

In the normal condition of the action, as illustrated in Fig. 1 of the drawings, the upper end of the finger is received within a seat or notch 19 formed in the lower portion of the front edge of the hammer block 9, with the hammer resting against the cushioned stop rail 11. When the free end of the key
100

is depressed, as in Fig. 3, the hammer is driven forward by the pressure of the finger or jack 16 in the notch or seat 19 of the block 9 until the shoulder or projection 19' knocks 5 the finger or jack 16 out of the notch or seat 19, the block 9 being cut away, as at 20, in order that the jack may continue to rise after it is released from the notch 19. When the hammer rebounds from the spring, the block 10 9 forces the jack 16 rearwardly upon its pivotal support 17 in order that said jack may not interfere with the proper rebounding of the hammer. Upon releasing the key, its inner end drops and the jack 16 is returned 15 into engagement with the notch 19 under the influence of the spring 15. The purpose of tripping or kicking the jack 16 out of the notch 19 is to prevent the jack from becoming wedged in the notch and thereby interfering with the proper rebounding of the 20 hammer from the string.

From the foregoing description, it will be seen that the present action is exceedingly simple and at the same time thoroughly effective, as the response of the hammer to the key is prompt and positive. Moreover, the action is constructed to permit rebounding of the hammer from the string while the key 25 remains depressed, whereby the sound given 30 out by the string is not muffled by the hammer but is clear and distinct.

It will be noted that the straight wall 19' of the seat 19 is inclined downwardly toward the jack 16 so as to form a lateral projection 35 or extension at the bottom of the seat which is of a length to engage the jack 16 just prior to the striking of the hammer head against the string, as in Fig. 2, thereby to positively

force the jack 16 out of the seat without the employment of any extraneous means. 40 The advantage of this feature is to prevent hanging of the jack in the seat and to disconnect the key and the hammer in order that the latter may be free to rebound from the string after striking the same. 45

Having thus described the invention, what is claimed is:

A key action comprising a key pivotally supported for manual operation, a hammer jack pivotally attached directly to the key, 50 and mounted to move positively and bodily therewith, a spring bearing at one end against the key and at its other end against said jack and having a tendency to expand longitudinally of the key, said jack having 55 its rear and upper surfaces rectangularly disposed toward each other, a vertically elongated hammer block pivoted adjacent the upper end of the hammer jack, a substantially vertical hammer stem attached to the 60 hammer block, a hammer carried by said hammer stem, said hammer block having a notch with its lower side substantially parallel with the hammer stem and its upper side convexed, the upper corner of the hammer 65 jack normally resting at the point of merger of the convex side and the side substantially parallel with the stem of the hammer block notch.

In testimony that I claim the foregoing as 70 my own, I have hereto affixed my signature in the presence of two witnesses.

MARTIN MILLER.
